HIS ATTORNEY

UNITED STATES PATENT OFFICE.

WILLIAM J. McDONALD, OF CHICAGO, ILLINOIS, ASSIGNOR TO PULLMAN CAR AND MANUFACTURING CORPORATION, OF CHICAGO, ILLINOIS, A CORPORATION OF ILLINOIS.

JOURNAL-BOX-LID CLOSER.

Application filed January 7, 1926. Serial No. 79,779.

My invention relates to journal boxes for railway cars and has particular reference to means operable by the lid of the box designed to draw the upper portion of the lid 5 against the box to insure a tight bearing thereof around the box opening.

Heretofore, the journal boxes have been fitted with lids having springs bearing against the hinge lug on the box. To insure 10 positive closure of the lid upon the box the springs were made of sufficient strength to transmit spring pressure at the box lug position to the lid at the box opening. With the lid held firmly to the box at the opening, 15 spring pressure in excess of that required for this purpose reacted upon the lid through the rigid connection between lid and spring. This caused the lid to fulcrum upon the box at its lower side and be forced out- 20 wardly from the upper side of the box opening; the stronger the spring the more pronounced the space between the upper side of the lid and adjacent edges of the box opening; with the spring tending to force the lid 25 outwardly the pin lugs on the lid would bear against the inner periphery of the hinge pin and press the pin against the forward side of the pin bearing in the box lug, causing the pin bearings to become elongated under 30 the stress of lid spring pressure and a further falling away of the lid as the wear at the pin bearings advanced. Efforts have 35 have been made to overcome these objections but since they involved merely the substitution of a flexible connection between the spring and lid and the concentration of spring pressure at the center of the lid they failed to accomplish the purpose intended 40 because none of them contemplated the removal of spring pressure from the box lug in the lowered position of the lid.

It is therefore the principal object of this invention to relieve the box lugs of lid spring pressure when the lid is in box closing position and cause such pressure to be received 45 by the mechanism connecting the box and lid.

A further and important object is to so correlate the lid spring and hinge pin that 50 actuation of the box lid to close the box will cause the pin to move inwardly and draw the adjacent portion of the lid tightly against the box.

The foregoing and other objects are attained by my invention, a preferred embodiment of which is illustrated in the drawings forming part of this specification and in which:

Fig. 1 is a vertical longitudinal section thru journal box and lid showing the position of the pin actuating mechanism when lid is down;

Fig. 2 is a similar view showing the position of the pin actuating mechanism when the lid is raised;

Fig. 3 is a perspective view of the parts just prior to the assembling operation showing the relation of the pin actuating mechanism parts and box and lid;

Fig. 4 is a vertical section thru the box lug showing the position of the hinge pin against the inner wall of its bearing in the lug when the lid is down; and

Fig. 5 is a similar view thru one of the lid hinge lugs showing the upper side of the lid drawn against the box.

In said drawings, 10 represents a journal box having the usual opening 11 defined by a lid seat 12; the box is supported upon axle journal 13 to which it is held by the custom-army brass 14 and wedge key 15. The box opening 11 is closed by lid 16 pivotally mounted at its lugs 17 upon pin 18 having a bearing in box lug 19, all in accordance with established practice.

The box lug 19 is slotted as best shown at 20 and in the present embodiment of the invention a separate lever arm 21 is entered in the slot in position to be engaged by a suitable spring 22 secured to lid 16; the lever arm 21 is mounted upon hinge pin 18 having a bearing in opening 23 of the lever arm; the arm is provided with a protuberant portion 24 and a normally inclined plane face portion 25 extending upwardly and outwardly from pin 18. The lever arm 21 is also formed with a depending portion 26 adapted for engagement with a recess 27 in the bottom of slot 20 as shown in Fig. 3. The recess 27 is preferably V-shaped in cross-section for a purpose to be presently described and proportioned to allow a limited rocking of the arm 21 during lid movement.

In operation, during movement of the lid 16 from the open or raised position shown in Fig. 2 to the lowered or closed position

shown in Fig. 1, hinge pin 18 is shifted inwardly from a position against the front wall of its bearing 28 in box lug 19 until it engages the rear wall thereof as shown in 5 Fig. 4. This movement is effected by means of lever arm 21 which yields under the pressure of lid spring 22 against inclined face 25 at a point above the axial center of the pin 18; the rotation of the lever arm with 10 or upon the pin will carry depending portion 26 forwardly against wall 29 of the V-shaped recess 27.

Further movement of the lid downwardly 15 will cause the spring 22 to bear upon face 25 of the lever arm and transmit pressure to slot wall 29 thru depending portion 26 of said arm, thereby effecting a translation 20 in the movement of the pin and lever arm from a pivotal to a bodily shifting of said members inwardly of the box as will be understood, carrying hinge pin 18 against the rear wall of pin bearing 30 in lid lugs 17 to draw adjacent portion of lid tightly 25 against seat 12 as shown in Fig. 5.

25 To raise the lid to the open position shown in Fig. 2 a reverse movement of the mechanism is effected; lid spring 22 will continue to exert pressure upon face 25 of lever arm 21 until the upper extremity of the spring 30 passes shoulder 24 on said arm when the pressure of the spring against upper face 31 of the lever arm 21 will cause said arm to be rocked forwardly until depending portion 26 thereof strikes the rear wall 32 of the 35 recess 27 as shown in Fig. 2 whereupon the rear wall of pin bearing 23 in the lever arm 21 will be thrust against pin 18 and force same against the forward wall of bearing 28 in the box lug 19 in which position of the 40 parts the lid will be held in the raised position indicated in this figure.

It should be noted that the application of 45 the lid closer mechanism described can be made to old or new journal boxes fitted with any standard American Railway Association lid, and that the mechanism is effective to pull the upper portion of the lid against the box regardless of the wear on hinge pin or pin bearings in box and lid lugs or character of lid spring employed.

Although a preferred form of the invention 50 is illustrated and described, it is obvious that various modifications thereof can be made. For example, the lever arm 21 55 may be made an integral part of the pin 18 and/or the pin may have offset portions at the lid lug bearings 30 to draw lid inwardly and the depending portion 26 on the lever arm dispensed with, provided always that 60 the power of the spring in excess of that required to hold the lid to its seat is directed against the hinge pin instead of the box as before explained.

What I claim is:—

65 1. The combination with a journal box

having a lid pivoted thereon, of a pin mounted for bodily movement on said box having operative connection with the lid, a spring carried by said lid, and an arm on said pin adapted for engagement with said spring 70 and effective during closing movement of said lid to cause said pin to draw the adjacent portion of the lid against the box.

2. The combination with a journal box having a lid pivoted thereon, of a lid closer 75 mechanism comprising a pin mounted for bodily movement on said box having operative connection with the lid, a spring on said lid, and means associated with said pin and operable by said spring to cause said pin to draw the adjacent portion of said lid against the box.

3. The combination with a journal box having a lid pivoted thereon, of a lid closer 80 mechanism comprising a pin mounted for bodily movement on said box having operative connection with the lid, a spring on said lid, and means intermediate said spring and box and below said pin operable by said spring to cause said pin to draw the adjacent portion of said lid against the box.

4. The combination with a journal box having a lid pivoted thereon, of a lid closer 85 mechanism comprising a spring carried by the lid, a pin connecting said box and lid and mounted for bodily movement with respect to said box, and a pin actuating lever arm on said pin operable by said spring to cause said pin to draw the adjacent side of said lid against the box.

5. The combination with a journal box having a lid, of a lid closer mechanism comprising a spring carried by the lid, a pin mounted for bodily movement with respect to said box and having operative connection 105 with said lid, and a lever arm adapted for engagement with said spring and box and operable by the spring to cause said pin to draw the adjacent side of the lid inwardly against the box.

6. The combination with a journal box having a lid therefor and a lid lug, of a lid closer mechanism comprising a spring carried by the lid, a lid pin mounted for bodily movement with respect to said box and having operative connection with said lid, a lever arm on said pin having direct engagement with said lid spring and box, said lug having a recess for receiving the box engaging portion of said arm, said lever arm being arranged to receive lid spring pressure in excess of that required to hold the lid closed to cause said pin to draw the adjacent side of said lid against the box.

7. The combination with a journal box 125 having a lid therefor, of a lid closer mechanism comprising a spring carried by the lid, a pin pivotally connecting said box and lid and shiftable bodily with respect to said box, and a lever arm on said pin operable 130

by said spring to cause said pin to draw the adjacent side of the lid inwardly against the box.

8. The combination with a journal box and lid therefor, of a lid closer mechanism comprising a spring carried by the lid, a pin pivotally connecting said box and lid and shiftable bodily with respect to said box, and a lever arm projecting upwardly from said pin and operable by said spring to cause bodily movement of said pin to draw the adjacent side of the lid against the box.

9. The combination with a journal box and lid therefor, of a lid closer mechanism comprising a spring carried by the lid, a pin pivotally connecting said box and lid, and a lever arm projecting upwardly from said pin and operable by said spring to cause bodily movement of said pin in the direction of pressure of said spring to draw the adjacent side of the lid against the box.

10. The combination with a journal box and lid therefor, of a lid closer mechanism comprising a spring carried by the lid, a pin pivotally connecting said box and lid, and a lever arm on said pin having an upwardly projecting arm portion adapted for engagement with said spring at a point above the axial center of the pin to cause

bodily movement of said pin in the direction of pressure of said spring to draw the adjacent side of the lid against the box.

11. The combination with a journal box having a lid and a recessed lug portion, of a lid closer mechanism comprising a spring carried by the lid, a pin pivotally connecting said box and lid, and a lever on said pin having upwardly projecting and depending arm portions rockable in said lug and engaging said spring at a point above the axial center of the pin and effective during the closing movement of the lid to cause bodily shifting of said pin in the direction of pressure of said spring to draw the adjacent side of the lid against the box.

12. The combination with a journal box and lid therefor, of a lid closer mechanism comprising a spring carried by the lid, a pin pivotally connecting said box and lid, and means on said pin operable by the spring to cause bodily movement of the pin in the direction of pressure of said spring during the closing movement of said lid to draw the adjacent side of the lid against the box.

In witness whereof I have hereto set my hand this 5th day of January, 1926.

WILLIAM J. McDONALD.
